IGNITION APPARATUS FOR LIQUID
FUEL FIRED FURNACESEdward George Simmons, Chiswick,
London, EnglandApplication May 19, 1944, Serial No. 536,355
In Great Britain May 26, 1943

4 Claims. (CL. 175—115)

1

This invention relates to ignition apparatus for liquid fuel-fired furnaces in which the liquid fuel is sprayed into the furnace combustion space from a fuel spraying or jet device.

A convenient method of igniting the oil used in such a furnace is to use an electrical sparking plug, but this leads to difficulty if the sparking plug is placed in the direct line of travel of the liquid fuel spray because it is very liable to become wetted by the liquid and, therefore, it will not give a spark. On the other hand, if the sparking plug is mounted in a position clear of the liquid spray path, ignition of the oil becomes very uncertain if not impossible.

The object of the present invention, therefore, is to provide means whereby the said difficulty may be overcome.

The above mentioned difficulty is overcome by the present invention, according to which I provide apparatus for use in igniting electrically the sprayed liquid fuel of liquid fuel-fired furnaces, which comprises a tubular member, the outermost end of which is adapted to support a sparking plug which forms a closure for that end of said member, the latter being mounted wholly or partly within the combustion space of the furnace in such a position that the outermost end of the member is outside the zone or path of the liquid fuel spray while the inner and open end of said member, which is formed to act in the manner of a scoop, projects into or adjacent to the said zone or path, the arrangement being such that while the spray or liquid-laden air is picked up by, or at, the open end of said member, the spray or liquid content is quickly deposited on the walls leaving only an inflammable vapour in the air. Thus, since no liquid is conveyed to the points of the sparking plug, the latter is not rendered ineffective but sufficient vapor-laden air is conveyed to the points of the sparking plug to provide an inflammable mixture which allows ignition to take place.

The said hollow member may consist of a short tube, one end of which is arranged to act like a scoop in the liquid fuel spray path or zone while the opposite end, which is kept outside the spray path or zone, is closed by the sparking plug.

The open end of the scoop tube, which projects into the liquid fuel spray path or zone, is arranged in such a manner as to catch a small amount of the liquid fuel spray together with some of the entrained air. The closed opposite end of the tube, carrying the sparking plug is arranged out of the liquid fuel spray path or zone. The scoop tube may be straight or curved and

2

its inner open end may be parallel to the axis of the spray path or inclined at an acute angle thereto.

The scoop tube may also be arranged wholly or partly within the furnace combustion space, and it may be so supported so that its open end may be moved into and out of the fuel spray path or zone either by hand or automatically.

A division plate may also be fitted in the scoop tube, so as to divide the latter into a channel for ingoing liquid-laden air and a channel for outgoing flame and products of combustion.

Constructional forms of the invention applied to oil-fired furnaces are shown, by way of example, on the accompanying sheets of drawings, whereon:

Fig. 1 is a fragmentary sectional view of the combustion space of an oil-fired furnace provided with ignition apparatus comprising a short curved scoop tube which is arranged wholly within the container space and is supported by a pivoted bracket.

Fig. 2 shows a modification in which the scoop tube is straight and is arranged partly within and partly outside the combustion space;

Fig. 3 is a view, partly in section, of the short, straight scoop tube of a modified-ignition apparatus, which is fitted with a division plate, the open end of the tube being shaped to act as a scoop for the spray or liquid-laden air;

Fig. 4 is a view corresponding to Fig. 3, but shows a modification in which the division plate acts as a scoop for the spray or liquid-laden air;

Fig. 5 is a fragmentary sectional view of a scoop tube which is similar to, and is arranged like, the tube shown in Fig. 3, but which has an inwardly-curved end; and

Fig. 6 is a fragmentary sectional view of a scoop tube which is similar to, and is arranged like, the tube shown in Fig. 4, but which has an inwardly-curved end.

Referring to Fig. 1:

The furnace comprises a circular combustion chamber 1 into which a fuel spraying device or jet 2 injects liquid fuel in a conical shaped spray 3. In the upper part of the spray, wholly within the combustion chamber, a curved scoop tube 4 is arranged with its open end just in the edge of the spray path and facing the direction of the spray. The inner, open end of the scoop tube may be cut either square (i. e., so that it is substantially parallel to the axis of the spray) or, as shown at 5, Fig. 1, at an angle to the axis of the spray but, in any case, such that it will act 55 in the manner of a scoop. The other end of the

tube is closed by a sparking plug 6. Liquid-laden air is caught in the open end 5 of the tube, the liquid particles being deposited on the inner walls of the tube and only vapour-laden air is carried up to promote ignition.

In an alternative construction shown in Fig. 2, the scoop tube 4A is made straight and is arranged partly within and partly outside the combustion space. The open end of the tube is bevelled at 7 to act as a scoop as described above.

In either case, the liquid fuel caught in the open end 5 or 7 of the tube 4 eventually drops out again in the form of large drops rather than fine particles. These drops, however, merely drop back into the flame and are consumed without causing any serious amount of smoke.

The scoop tube 4 and sparking plug assembly 6 may be mounted on a bracket 8 pivotally arranged at 9 in the combustion chamber 1 so that once ignition of the main furnace has been obtained, the tube may be swung out of the actual path of the liquid spray. The removal of the tube out of the spray path may either be performed by hand or thermostatically. In the latter case, the bracket 8 may be made of thermostatic bi-metal strip and may be fixed at its end remote from the scoop tube instead of being hinged. Thus, as soon as ignition of the fuel takes place and combustion commences, the heat radiated back on to the bi-metal strip causes it to flex and withdraw the open end of the tube from the actual spray path.

In a further modification, in order to promote a more positive circulation of vapour-laden air to the sparking plug points, a division plate is fitted into the tube in such a manner as to form two longitudinal passages, one for ingoing spray or liquid-laden air and one for out-going flame and products of combustion. The arrangement at the open end may either be as described above, in which the tube forms a scoop, or the dividing plate itself may be shaped to do so.

The length of the division plate will depend on circumstances, but in no case should it extend right up to the sparking plug as it is necessary to leave a cross passage so that the flame and products of combustion air can find their way out through the outgoing passage.

Thus, as shown in Fig. 3, the scoop tube 4B is straight and is fitted with a division plate 9 which extends centrally of the tube and terminates short of the points of the sparking plug 6A. The outer end of the division plate projects out of the sloping inner end 10 of the tube 4B, the projecting end of the plate being curved towards the fuel spraying device or jet (not shown) but arranged outside the fuel spray path or zone. The inner end 10 of the scoop tube is cut at an angle to the axis of the tube and faces the fuel spraying device, the part 11 of the angled end of the tube being arranged just within the spray path 3A so that it acts as a scoop for the spray or liquid-laden air. The division plate 9 thus forms within the tube an inlet channel 12 for the vapour laden air, which latter flows inwards of the tube to the back of the division plate and, then through the space between the inner end of the plate and the sparking plug points. The flame and products of combustion pass outwards through the outlet channel 13 on the opposite side of the plate. In this case, the division plate itself does not act as a scoop.

The construction shown in Fig. 4 is similar to that shown in Fig. 3 but it differs therefrom in that the inner end 10A of the scoop tube 4C is

square to the axis of the tube and penetrates only slightly, if at all, into the fuel spray 3B while the curved outer end of the division plate 9A projects into the fuel spray and thus acts as a scoop. In this construction, the plate divides the tube into an inlet channel 12A for the spray or liquid-laden air and an outlet channel 13A for the flame and products of combustion.

In the constructions shown in Figs. 5 and 6, the inner ends of the scoop tubes are curved towards the fuel spraying or jet device. In Fig. 5, the part 11A of the angled end 10B of the tube projects into the path 30 of the fuel spray and thus acts as a scoop, while the curved end of the division plate 9B, which projects out of the tube, terminates short of the said spray. The division plate acts to divide the tube into an inlet channel 12B for the spray or liquid-laden air and an outlet channel 13B for the flame and products of combustion but it does not act as a scoop.

In the construction shown in Fig. 6 the inner end of the scoop tube 4D is also curved and the curved end of the division plate 9C, which divides part of the length of the tube into inlet and outlet channels 12C and 13C for the spray or liquid-laden air and the flame and products of combustion respectively projects out of the scoop tube into the path 3D of the spray. The plate thus acts as a scoop for the spray or liquid-laden air.

I claim:

1. Apparatus for use in igniting electrically the sprayed liquid fuel of liquid fuel-fired furnaces, which comprises in combination, a tubular member, means mounting said tubular member in the furnace whereby the inner end at least of the tubular member will be within the combustion space of the furnace, a sparking plug supported in the outermost end of said tubular member and acting as a closure for said end, the tubular member being of such a length that the points of the sparking plug are enclosed within the tubular member and thus shielded from the liquid fuel spray, the inner end of said tubular member being open and intersecting the fuel spray, and a division plate being disposed lengthwise and within said tubular member and disposed in spaced relation from said sparking plug, whereby while the spray or liquid laden air is picked up at the inner open end of said member, the spray or liquid content is quickly deposited on the walls of said member leaving only an inflammable vapor in the air and, since no liquid is conveyed to the points of the said sparking plug, the latter is not rendered ineffective, but sufficient vapor-laden air is conveyed to the points of the sparking plug to provide an inflammable mixture which allows ignition to take place.

2. The apparatus claimed in claim 1, wherein the inner end part of said tubular member is curved inwards towards the axis of the fuel spray.

3. The apparatus claimed in claim 1, wherein the said tubular member is secured to and supported by a bracket which is fixed at its end remote from said member and consists of a thermostatic bi-metal strip, whereby as soon as ignition of the fuel has taken place, the heat radiated back on to the strip causes it to flex and withdraw the open end of the said tubular member away from the fuel spray path.

4. The apparatus claimed in claim 1, wherein said division plate is fitted in said tubular member in such a position that two longitudinal channels are thereby formed in the tube, one for ingoing spray or liquid-laden air and the other

for outgoing flame and products of combustion, and a cross passage adjacent to the sparking plug connecting these two channels, the division plate being extended from the inner end of said tube and shaped to act as a scoop.

EDWARD GEORGE SIMMONS.
